BRASSIÈRE

Margia K. Childs, Jacksonville, Tex.

Application April 22, 1938, Serial No. 203,692

3 Claims. (Cl. 2—42)

The present invention relates to women's under garments and more particularly to improvements in brassières.

It is well recognized that brassières are worn under the outer clothing to afford ease and comfort to the wearer and at the same time preserve the natural form or contour of the body. Heretofore, it has been customary to employ a body encircling member formed with pockets or the like that are adapted to encompass the breasts and support the same in the proper position. These garments have further been provided with shoulder straps for holding the body encircling member in the desired location and separable fasteners attached to the rear of the garment for enabling the same to be fastened to the body of the wearer.

The garments above referred to, however, have not proven completely satisfactory. In the first place, they are somewhat uncomfortable, and in the second place, they do not afford sufficiently natural support for the breasts.

An important object of the present invention is to provide a brassière that will overcome the above and other undesirable features.

Another object of this invention is to provide a brassière that will always support the breasts in an attractively upright and desirable position.

Still another object of this invention is to provide a brassière in which the breast supporting pockets are provided with reinforced portions which substantially improve the form fitting characteristics thereof.

In order to achieve the above and other objects, the brassière includes a pair of conically shaped pockets that are adapted to fit snugly over the breasts. The pockets are preferably formed with an upper portion and a lower support portion.

One means of affording the necessary reinforcing to the pockets, is to provide a series of lines or rows of stitches that describe a spiral about the apex of the pocket, the lines of stitches beginning and terminating in the lower support portion to form therein a series of overlapped rows of stitches. These overlapped rows of stitches in the lower portion of the pocket greatly increase the supporting efficiency thereof and provide a means for firmly holding the breasts in an upright position.

I have also found that a satisfactory pocket member may comprise a lower support portion reinforced by a series of overlapped rows of stitching and an upper portion having no reinforcing stitching.

The present invention, however, has other ad-

vantageous features and possesses additional objects that will become apparent from a study of the embodiments of the invention illustrated herein.

To facilitate an adequate comprehension of my invention, reference is directed to the accompanying drawing which illustrates the preferred form of my inventive concept, it being understood, however, that numerous changes may be made therein by those skilled in the art without exceeding the scope of my invention as described by the annexed claims.

Referring to the drawing in which like numerals designate similar parts:

Fig. 1 is a front elevational view of a brassière depicting one form of my invention.

Figure 2 is a side elevational view of the garment shown in Figure 1.

Figure 3 is a detailed view of the various elements which when assembled form the brassière pocket as illustrated in Figure 1.

Figure 4 is a front elevational view partly broken away showing a modified form of my inventive concept.

Figure 5 is a front elevational view of the center section of my brassière as shown in Figure 1.

Figure 6 is a front elevational view of a modified pocket member.

Referring now to the drawing, and particularly Figure 1, there is illustrated a brassière having conically shaped pockets or breast encircling portions 1 and 2. The pockets can be made of any desirable material, such as silk, lace, net or any fabric that will readily conform to the configuration of the breasts of the wearer. It will be noted that side portions 3 and 4 are disposed adjacent the pockets 1 and 2 and extend beneath the arms of the wearer. Each side portion tapers downwardly from its juncture to the pockets, as shown at 6 and an elastic element 7 is suitably secured to the portion 3. The opposite end of the element 7 carries suitable fastening members adapted to engage corresponding fasteners secured to the side portion 4 in order to secure the garment around the body of the wearer.

In addition, adjustable shoulder straps 10 of any desirable structure and material are suitably attached to the garment for extending over the shoulders, thereby holding the brassière in the correct position.

To provide a more natural separation of the breast, it will be seen that a fabric member 11 of relatively stout material is positioned between

the pockets 1 and 2 and attached thereto. As clearly depicted in Figure 5, the member 11 is provided with portions 12 and 13, that extend beneath the lower edges of the pockets 1 and 2 and over the lower mid portion of the brassière. It will further be noted that the mid portion of the garment is fashioned at the lower edge as shown at 14.

An elastic strap 15 extends horizontally beneath the portion 14 and is attached at each end to extensions 12 and 13. It is manifest that the elastic strap 15 will urge the fabric member 11 inwardly between the breasts and maintain the pockets 1 and 2 closely in position over the breasts.

To assure a proper configuration of the breasts, reference is directed to Figure 3 wherein is illustrated the manner in which the pockets 1 and 2 are formed. Fabric members 17 and 18 show the design of the two lower portions forming pocket members 1 and 2 as described in connection with Figure 1. A fabric member 19 shows the design of the upper portion of the pockets. A notch 20 formed in the member 19 affords the necessary conical effect for the pocket. The fabric members 17, 18 and 19 are adapted to be stitched together as depicted by the seams 21.

As previously mentioned, an important feature of this invention is the provision for reinforcing the breast encircling pockets. In Figure 1, it can be seen that the lower portion of the pocket 2 is provided with a plurality of rows of stitches 23. The said rows of stitches describe a spiral about the apex of the cone of the pocket substantially terminating adjacent to the line of juncture of the pocket to the side portion 4. By thus arranging the rows of stitches, there will be formed a plurality of substantially parallel rows of stitches 22 in the upper portion of the pocket, and a plurality of overlapped rows of stitches 23 in the lower portion. Obviously, the overlapped rows 23 in the lower portion of the pocket will materially strengthen the supporting area thereof and will thereby maintain the breast 45 in a firm upright position.

It is to be understood, however, that the overlapped rows of stitches 23 can be formed in other ways and the particular arrangement shown herein is for the purpose of illustrating my inventive concept.

It will be appreciated from the foregoing that the fabric member 11 in conjunction with the elastic strap 15 will affect a separation of the breasts and the shape of the pockets 1 and 2 together with the overlapped rows of stitches 23 will maintain the breasts in an attractively upright and desirably natural position.

In Figure 4, there is shown a modified form of my garment. In this embodiment, the pockets 60 are formed with a lower supporting section 24 that is preferably made of fabric, such as silk. The upper section 25 is formed of net or lace and is attached to the lower section 24. The lower and upper sections 24 and 25 may be suitably secured to the fabric side portion 4' in any desirable manner.

In this modification it will be seen that the inner edge of the upper section 25 tapers downwardly thereby maintaining the desired separation of the breasts. However, in order to further facilitate a more natural separation and support of the breasts, elastic strap 27, 27' secured to the top portion of the pocket, extend along the edge of top section 25 substantially parallel with 75 the tapered portion of the pocket to a vertically

positioned fabric strip 28 at the midpoint of the brassière.

Clearly, the elastic member 27, 27' will firmly hold the inner pocket portions of the garment so as to affect a support means capable of maintaining the breasts in a desirably upright and natural position.

It will be observed that overlapping rows of stitching 23 for reinforcing the lower portion of the pocket members are arranged in substantially 10 the same manner as those described with respect to Figure 1. It will also be observed that while the upper portion of the pocket member extends downwardly from a point at the apex of the pocket, along the lines of juncture 26 with the 15 lower portion, the arrangement, whereby substantially parallel rows of stitching beginning and terminating in the lower pocket portion so as to form a series of overlapped rows in the lower portion is substantially the same as shown in 20 Figure 1.

In Figure 6 I have shown a modified stitching arrangement for a brassière pocket. In this embodiment, in the lower pocket portion 30, overlapping rows of stitching, substantially as shown 25 in Figures 1 and 4, serve as the support means for the pocket members. It will be seen that substantially parallel rows of stitching are terminated at the lines of juncture of the upper and lower pocket portions and, as shown, do not extend into the upper pocket portion 29.

It is understood that either arrangement of stitching as for example the arrangement as shown in Figures 1, 2, and 4 or the modification, as shown in Figure 6 is adaptable for use in substantially any style brassière as for example as shown in Figures 1 or 4.

While I have illustrated and described the preferred form of my invention, it is to be understood that I am to be limited only by the prior 40 art and the scope of the appended claims.

I claim:

1. A bust molding and supporting construction comprising a pair of breast-receiving pockets preformed to approximately conical shape, and a 45 plurality of lines of stitches carried by each of said pockets, said lines of stitching originating and terminating in the lower half of each pocket and extending from one side of the lower half toward the other side, then passing upwardly into 50 the upper half, encircling the apex of the pocket, entering the lower half on the side of origination, crossing themselves in the lower half of the pocket, and then extending into said other side of the lower half to form an overloop, the ends of 55 said loop extending in a virtually horizontal plane in said lower half of the pocket, whereby said stitching forms side to side tension members adapted to resist sagging of the breast while permitting the upper portion to be suitably molded. 60

2. A breast pocket construction comprising a preformed stitched breast-receiving pocket of approximately conical shape made from a flexible open material, and a plurality of spaced virtually parallel lines of stitching extending from one 65 side of the lower half of said pocket, describing a reverse loop in the upper half, crossing themselves in the lower half, and extending into the opposite side of the lower half whereby said stitching forms side to side tension members adapted to 70 resist sagging of the breast contained in said pocket.

3. A bust molding and supporting construction comprising a pair of attached breast-receiving pockets preformed to approximately conical 75

shape, and a plurality of parallel curved lines of 5
stitches carried by each of said pockets, said
curved lines of stitching originating in the lower
half of each pocket and extending from one side
of said lower half upwardly toward the other
side, then passing into the upper half and concent-
rically semi-circling the apex of the pocket to
form a series of concentric loops, then extending
downwardly to the rear, entering the lower half
10 of the pocket and terminating in the lower half

at the side opposite the side of origination; the
extended ends of the plurality of such series of
loops crossing themselves in the lower half of
the pocket whereby said stitched lines create ten-
sion members in a criss-crossed diamond-shaped
pattern adapted to resist and support the lower
portion of the breasts while permitting the upper
portion to be suitably molded. 5
